SPACEBAND WIPING DEVICE

Gerald S. Fuller, Schenectady, N. Y.

Application July 17, 1941, Serial No. 402,767

8 Claims. (Cl. 199—62)

My invention relates to space band wiping devices for wiping, cleaning, and applying a wiping material or lubricant to the short sleeves of space bands used in any conventional print line-casting machine.

Print line-casting machines are adapted to provide for the arrangement of matrices in a row in accordance with any desired order with a space band between groups of matrices forming different words. Molten type metal may then be cast against the matrices and space bands to form a line of type. Since all lines do not have the same number of letters and spaces, each space band is made of two relatively movable wedge-shaped elements, which comprise a relatively short sleeve and a relatively long wedge which is slidable on the short sleeve to provide various thicknesses of space bands between words in different lines by "justifying" each line to space apart all words evenly in each line. When the matrices and space bands have been "justified," molten type metal is cast under high pressure against the casting side of the matrices and the space bands. "Justification" of the space band places the long wedges of the space bands in a different position relative to the casting metal each time they are used, so that there is substantially no tendency for the type metal to adhere to them. The short sleeve of the space bands, however, always presents the same portion of the casting edge thereof to the molten metal, with the result that eventually a slight corrosion occurs and type metal adheres to the sleeve at the casting point. This causes high spots on the sleeve adjacent depressions in the matrices and will cause hairlines between the words in a line, which may even damage the ink roller and the paper besides creating unsightly printing of hairlines between words. Attempts have been made to prevent this oxidation and adherence of metal to the bands by applying various materials to the surfaces of the bands and by wiping them under pressure. All of these methods have either resulted in the use of too much cleaning or lubricating material applied indiscriminately to the bands with the result that the wiping material and graphite on the bands formed a sticky paste, such that the bands would not "justify" properly, or the act of wiping and applying lubricant markedly reduced the speed of the band through the space band chute, such that it appeared between the wrong letters in the completed line.

An object of my invention is to provide an improved wiping device for cleaning space bands

and preventing or minimizing the adherence of type metal to the bands.

Another object of my invention is to provide an improved wiping device for cleaning space bands.

Further objects and advantages of my invention will become apparent and my invention will be better understood from the following description referring to the accompanying drawing, and the features of novelty which characterize my invention will be pointed out with particularity in the claims appended to and forming a part of this specification.

In the drawing, Fig. 1 is a side elevational view 15 of a space band box and associated parts provided with an embodiment of my improved wiping device and partly broken away to show the relative arrangement of the device and the box with space bands therein; Fig. 2 is an elevational view of the chute plate and wiping device taken along line 2—2 of Fig. 1; Fig. 3 is an elevational view of the front of the upper part of the chute plate and the wiping device shown in Fig. 1, illustrating the relative positions of the wiper 20 and the upper part of a space band in the position when it is released from the box and begins its passage down through the box chute; Fig. 4 shows a space band with an application of lubricant or wiping material thereon; and Fig. 5 is a perspective view of the wiper shown in Figs. 1 to 3, inclusive.

Referring to the drawing, I have shown a conventional space band box having side plates 10 to which top rails 11 are secured for supporting a plurality of space bands in the box. Fingers or shoulders 12 on short wedge sleeves 13 of space bands extend over the top rails 11 of the box and a center bar 14 and center bar bracket 15 are arranged between the top rails 11 over the sleeve 25 fingers 12 to retain the space bands in position in the box and to urge them toward a box chute 16 formed in the front of the box at the upper portion by a chute plate 17 and at the lower portion between outer and inner chute plates 18 and 19, respectively. The inner lower chute plate 19 is formed with an inwardly curved upper portion providing a funnel-shaped opening adjacent the lower ends of long wedges 20 of the space bands. As shown in Fig. 1, the space bands are held in the box at an angle to the vertical with the lower end of the long wedges further from the chute plate 17 than the upper ends of the space band sleeves 13, such that when the sleeve fingers 12 of the outermost band are raised 30 preparatory to being released, the lower end of

the long wedge 20 is raised over the upper edge of the curved inner chute plate 19 and swings forward toward the upper chute plate 17. This motion insures that the space band falls into the chute when released from the rails 11 by the space band box pawl.

In order to wipe and clean the short sleeves of the space bands of any corrosion or metal deposit on the outer flat side face at the casting point 21 adjacent the casting edge 22 thereof, I provide a wiping device including a wiper element holder 23, which is pivotally supported on the space band box by a pivot pin 24 extending through the upper end of the holder 23 and rotatably mounted in sockets 25 formed in the upper chute plate 17. This wiper holder 23 is arranged in an aperture 26 formed in the upper end of the chute plate 17 and the pivot pin 24 is permanently mounted in the sockets 25 by welding a small deposit of metal over grooves forming the sockets 25 to prevent accidental dislodgement of the wiper. The welded side of the socket 25 is ground smooth with the adjacent side of the chute plate 17 to present a clean finished outer surface. As is more clearly shown in Fig. 3, the aperture 26 extends for a width transversely across the chute plate 17, such that the casting edge 22 of the space band sleeve 13 is exposed as it passes downwardly in the chute 16. I have found that corrosion and deposition of type metal on the short sleeve side face at the casting point can be minimized if a thin film of non-metallic material be applied to the short sleeve adjacent and over the casting point 21. My wiping device is arranged to apply such a wiping or lubricating material by a wiper element 27 of any suitable material, such as carnauba wax and graphite or absorbent material, such as felt, impregnated with oil or similar lubricant or wiping and cleaning liquid, mounted in a pocket 28 formed in the holder 23. A wiping liquid supply passage 29 is formed in the holder to replenish the lubricant of the wiper element 27, if it be made of absorbent material, and the wiper 27 is gravity biased inwardly of the chute 16 by a weight formed as an enlarged portion 30 on the outer lower end of the wiper holder 23 on the side opposite the wiper pocket 28.

It is of utmost importance to apply the proper amount of lubricant over the correct portion of the space band to obtain the desired cleaning and to minimize metal deposition. If the long wedge 20 be contacted by the wiper such that lubricant is applied thereto or to the lower edge of the short sleeve 13 or if too much lubricant is used and passes to these parts of a space band, it forms a sticky or gummy paste with the graphite, which prevents or greatly hinders free relative sliding of the short sleeve 13 and the long wedge 20, thereby aggravating rather than remedying an undesirable condition. Furthermore, if the wiper contacts the lower edge portion or the upper portion or fingers 12 of the short sleeve 13, it may retard the downward passage of the space band, such that the band may fall between the wrong letters in a line with a resultant misspelling of two words. I have found that all of these features must be carefully considered to provide for the successful operation of this type wiping device. In order to provide the desired wiping action and to apply the lubricant properly, I form the wiper element 27 with a tapered wiping face 31 having the portion 32 thereof adjacent the casting edge of the space

bands extending further into the chute 16 from chute side of the holder 23 than the other end portion 33 of the face 31. The width of the inwardly projecting portion 32 of the wiper 27 extends transversely in the aperture 26 in a position such that it contacts the short sleeve 13 slightly below and slightly inwardly of the contact point 21 and in substantial vertical alignment therewith, as a space band is released into the box chute in the position shown in Fig. 3. Furthermore, the wiper element 27 and the holder 23 are proportioned and arranged so as to provide for application of lubricant and contact of the wiper 27 with the flat side of the short sleeve 13 over a small area on all sides of the casting point 21. This provides a thin film of lubricant 34 over the desired area, as shown in Fig. 4. When a space band is released, the outwardly swinging movement of the lower end of the long wedge 20 brings the short sleeve 13 into almost immediate wiping contact with the wiper element 27, and as the speed of the band increases and it gains momentum, the pressure between the sleeve and the wiper also increases as the band tends to continue its outward movement toward the wiper 27 and the chute plate 17. By properly weighting the portion 30 of the holder 23, the impact of the short sleeve 13 on the wiper 27 will cause it to swing pivotally outwardly, and contact of the wiper with the sleeve will stop slightly above the casting point 21 substantially when the band has moved outwardly into the chute to the upper chute plate 17, when further outward movement of the band is stopped, while the momentum of the weighted holder causes it to swing further outwardly and then to return to its inwardly biased position after the upper end of the band has passed down in the chute 16 past the wiper 27, thus insuring wiping and application of lubricant to just the desired area adjacent and over the casting point of the space band during a substantially predetermined passage of a band through the chute without contacting or applying wiping material to the long wedge or the upper or lower portions of the short sleeve.

While I have illustrated and described a particular embodiment of my invention, modifications thereof will occur to those skilled in the art. I desire it to be understood, therefore, that my invention is not to be limited to the particular arrangements disclosed, and I intend in the appended claims to cover all modifications which do not depart from the spirit and scope of my invention.

What I claim as new and desire to secure by Letters Patent of the United States is:

1. A space band wiping device for a space band box having a chute comprising means including a wiper element arranged to contact a space band short sleeve below and in substantial vertical alignment with the casting point for wiping the short sleeve and applying a lubricant thereto on the flat surface of the outer side of the sleeve over the casting point of the sleeve on passage of a space band through said chute of said space band box without contacting the space band long wedge, and means for supporting said wiper element on said box.

2. A space band wiping device for a space band box having a chute comprising means including a wiper element arranged to contact a space band short sleeve below and in substantial vertical alignment with the casting point for applying a wiping material thereto on the flat surface of the

outer side of the sleeve over the casting point of the sleeve on passage of a space band through said chute of said space band box without applying wiping material to the space band long wedge and the lower portion of the short space band sleeve, and means for supporting said wiper element on said box.

3. A space band wiping device for a space band box having a chute comprising means including a wiper element arranged to contact a space band short sleeve below and in substantial vertical alignment with the casting point thereof for wiping the short sleeve and applying a wiping material thereto on the flat surface of the outer side of the sleeve without applying wiping material to the space band long wedge and the upper and lower portions of the short space band sleeve on passage of a space band through said chute of said space band box, and pivotal means for supporting said wiper element on said box.

4. A space band wiping device for a space band box with a chute including means for wiping and for applying lubricant on the outer side of the short sleeve of a space band below and in substantial vertical alignment with the casting point thereof after release of a space band for passage through said chute without applying lubricant to the space band long wedge, and gravity means for providing an increase in pressure of said wiping means on the short sleeve with continued movement of a band for a substantially predetermined passage of a band through said chute toward said wiping means.

5. A space band wiping device including a chute plate having an aperture adjacent the upper end thereof, and means including a wiper element pivotally supported on said chute plate in said aperture arranged to contact the outer flat side of a space band sleeve below and in substantial vertical alignment with the casting point on the casting edge thereof for wiping the sleeve at and adjacent the sleeve casting point without contacting the space band long wedge or the upper and lower portions of the space band sleeve on passage of a space band past said chute plate aperture.

6. A space band wiping device for a space band box with a chute including means for wiping and applying wiping material on the outer side of the short sleeve of a space band below and in substantial vertical alignment with the casting point thereof after release of a space band for passage through said chute without wiping or applying wiping material to the space band long wedge and the upper and lower portions of

the short sleeve, and means for providing an increase in pressure of said wiping means on the short sleeve with continued movement of a band for a substantially predetermined passage through said chute toward said wiping means.

5 7. A space band wiping device including a chute plate having an aperture adjacent the upper end thereof, said aperture extending transversely across said chute plate for a width adapted to expose the casting edge of a space band on passing said aperture, a wiper element holder, means for pivotally supporting said holder to extend into said aperture, and means including a wiper element arranged to contact the outer flat side of a space band sleeve adjacent the casting point on the casting edge thereof for wiping the sleeve and applying wiping material to the sleeve at and adjacent the sleeve casting point without contacting the space band long wedge and the upper and lower portions of the space band sleeve on passage of a space band past said chute plate aperture, said wiper element having a tapered wiping face with the portion thereof adjacent the casting edge of a space band extending further from the chute side of said holder than the other portion of said face.

10 8. A space band wiping device including a chute plate having an aperture adjacent the upper end thereof, said aperture extending transversely across said chute plate for a width adapted to expose the casting edge of a space band on passing said aperture, a wiper element holder having a wiper element retaining pocket and a wiping liquid supply passage communicating with said pocket, means for pivotally supporting said holder to extend into said aperture, means including a weight on said holder for biasing said holder by gravity inwardly toward the chute side of said chute plate, and means including a wiper element of absorbent material supported in said holder pocket and arranged to contact the outer flat side of a space band sleeve adjacent the casting point on the casting edge thereof for wiping the sleeve and applying wiping liquid to the sleeve at and adjacent the sleeve casting point without contacting the space band long wedge or the upper and lower portions of the space band sleeve on passage of a space band past said chute plate aperture, said wiper element having a wiping face with the portion thereof adjacent the casting edge of a space band extending further from the chute side of said holder than the other portion of said face.
